UNITED STATES PATENT OFFICE.

CHARLES M. PRIOR, OF NEW YORK, N. Y., ASSIGNOR TO INTERNATIONAL SILVER CO., OF MERIDEN, CONNECTICUT, A CORPORATION OF NEW JERSEY.

DESIGN FOR A HANDLE FOR SPOONS, FORKS, OR SIMILAR ARTICLES.

No. 37,931.

Specification for Design.

Patented April 3, 1906.

Application filed February 6, 1906. Serial No. 299,841. Term of patent 7 years.

To all whom it may concern:

Be it known that I, CHARLES M. PRIOR, a citizen of the United States, residing at New York, in the county of New York, and State of New York, have invented a new, original, and ornamental Design for a Handle for a Spoon, Fork, or Similar Article; and I do hereby declare the accompanying drawing to be a full, clear, and exact illustration of the same, and which said drawing constitutes

part of this specification and represents a face view of a handle for a spoon, fork, or similar article embodying my design.

I claim—

The ornamental design for a handle for a spoon, fork or similar article, as shown.

CHARLES M. PRIOR.
